UNITED STATES PATENT OFFICE.

WALTER P. MURPHY, OF CHICAGO, ILLINOIS.

RELEASE-RIGGING FOR CAR-COUPINGS.

1,151,376.

Specification of Letters Patent.

Patented Aug. 24, 1915.

Application filed December 27, 1913. Serial No. 809,033.

To all whom it may concern:

Be it known that I, WALTER P. MURPHY, a citizen of the United States, residing at Chicago, in the county of Cook and State of Illinois, have invented certain new and useful Improvements in Release-Riggings for Car-Couplings, of which the following is a specification.

In the drawings, Figure 1 is a top plan view of a car, broken away, showing my improved release rigging attached. Fig. 2 is an end elevation of the same. Fig. 3 is an enlarged detail top plan view of the hand operated lever. Fig. 4 is a front elevation 15 of the same. Fig. 5 is an enlarged detail top plan view of the pin lever. Fig. 6 is an enlarged detail front elevation of the pin lever. Fig. 7 is a detail sectional view on the irregular line 7-7 Fig. 2, the levers being removed looking in the direction of the arrows. Fig. 8 is a front elevation of a 20 release rigging embodying my invention, attached to a car, adapted to operate a bottom operating coupler. Fig. 9 is a top plan view of Fig. 8. Fig. 10 is a top plan view 25 of a release rigging showing another embodiment of my invention. Fig. 11 is a front elevation of Fig. 10. Fig. 12 is a detail top plan view of a modified form of fastening between the ends of the levers. Fig. 13 is a detail top plan view of the 30 levers showing still another type of fastening between the ends of the levers. Figs. 14, 15 and 16 are, respectively a top plan, an 35 end and a front elevation of the hand lever fulcrum.

The reference numeral 1 designates a car, broken away, 2, the draw bar, 3 the coupler lock pin and 4 the end sill.

40 In carrying out my invention it will be understood that I do not limit myself to the exact application of the fulcrums as shown, as this is governed, to a great extent, by the design of the car.

45 The pin lever fulcrum 5 has an integral base 6 which is secured to the end sill by means of the rivets 7 as more clearly shown in Fig. 7. The fulcrum 5 has at its outer end an elongated bearing 8 terminating in a 50 shoulder and a screw threaded portion on which the washer 9 is secured by means of the nut 10, the washer bearing against said shoulder.

The fulcrum 11 for the hand operated 55 lever is provided with an integral bracket 12 which is secured by means of the rivets

13 (one only being shown) to the base flange of the channel end sill.

14 is a washer and 15 a nut on the outer end of the bolt 16, said bolt passing through 60 one leg of the bracket and through the fulcrum.

The hand lever 17 is pivotally mounted on the fulcrum 11 and secured thereon by means of the washer 14, bolt 16 and nut 15: 65 the outer portion 18 of the hand lever 17 is offset forwardly from the remainder thereof and when in operative position on the car is beneath the plane of the under face of the car as clearly shown; the inner portion of 70 the head lever 17 is deflected upwardly at an angle to the remainder and terminates in an elongated bearing pin 19 having an offset end 20 serving as a stop to retain the lever 21 on the bearing pin 19. This bearing 75 19 extends forwardly from the car when the lever is secured to the car. The pin lever 21 is pivotally mounted, intermediate its ends, on the elongated bearing 8 of the fulcrum 5 heretofore described in detail. 80 The inner end of the lever is operatively connected with the locking pin 3 as shown. The outer end portion of the pin lever 21 is, in the preferred form, provided with an elongated slot 22, in which the bearing pin 85 19, of the hand lever, is journaled or positioned, so that when the hand lever is pulled upward, its inner end is swung downward and by reason of the independent fulcrums of the two levers and the pin and slot connection between said levers, an upward 90 movement of the inner end of the pin lever is produced which lifts the coupler lock pin 3.

In Figs. 8 and 9 I have shown my invention adapted to operate a bottom operating 95 coupler. It will be observed that the cross sectional area of the pin lifting lever 21, as compared with the length of the fulcrum bearing 8 and the pin 19, is such that it may move bodily thereon to accommodate 100 the movement of the coupler in buffing and draft, therefore no strain is imposed on either of the levers.

In Figs. 10 and 11 I have shown the outer end of the pin lever 23 and the inner end of 105 the hand lever 24 connected together by means of the bolt and nut 25 there being a slot 25^a in one of the levers indicated by dotted lines whereby a pin and slot connection is formed between the levers.

In Fig. 12 I have shown the outer end of the bearing 26 of the hand lever 27 pro-

110

vided with a nut 28 threaded thereon, said nut acting as a stop to retain the pin lever 29 on said bearing.

As shown in Fig. 13 the pin lever 30 may be provided with the bearing pin 31 and the hand lever 33 provided with the elongated slot 32, to provide the pin and slot connection between the two levers.

I claim:—

1. In a release rigging for car couplers, a vertically movable pin operating lever pivoted to a car intermediate its length to provide bodily movement thereof to and from said car, of a hand operated lever pivoted intermediate its length to a car, and a connection between the adjacent ends of said levers, said connection providing an elongated pivotal bearing of one of said levers on the outer of said levers, whereby said bodily movement of said pin lever is permitted.
2. In an uncoupling rigging for car couplers, a hand operated lever pivoted intermediate its ends on the end of car, a pin lifting lever pivoted intermediate its ends on the end of the car, an elongated pivotal bearing for said pin lever, secured on the end of the car, and an elongated pivotal bearing on the hand operated lever on which the outer end of the pin lever is mounted whereby the pin lever is free to move bodily toward and away from the car to accommodate the movement of the coupler in buffing and draft.
3. In an uncoupling rigging for car cou-

plers, the combination with a pin lever pivotally mounted intermediate its ends, on the end of a car, of a hand operated lever independently pivotally mounted intermediate its ends on the end of the car, the inner end thereof being deflected upwardly to the plane of the pin lever with which it has a pin and slot connection, the outer portion of the hand lever being out of the plane of the remaining portion and sagging downwardly and forwardly, and disposed, when not in operation, beneath the plane of the under face of the car, and adapted to be moved upwardly to operate the pin lever.

4. In an uncoupling rigging for car couplers, a hand operated lever pivotally mounted, intermediate its ends, on the end of a car, and having its inner portion terminating in an elongated pivotal bearing for a pin lever, an elongated pivotal bearing secured to the end of a car, a pin lever pivotally mounted intermediate its ends, on the pivotal bearing which is secured to the car, the outer end portion of the pin lever having an elongated slot in which the pivotal bearing on the hand lever is journaled, whereby the pin lever may move bodily with the coupler in buffing and draft.

In testimony whereof I affix my signature in presence of two witnesses.

WALTER P. MURPHY.
